DESIGN FOR A WATER HEATING APPARATUS

Garry Sands, Cleveland Heights, Ohio, assignor to The Sands Manufacturing Company, Cleveland, Ohio, a corporation of Ohio

Application April 19, 1937, Serial No. 68,868

Term of patent 7 years

To all whom it may concern:

Be it known that I, Garry Sands, a citizen of the United States, residing at Cleveland Heights, Cuyahoga County, Ohio, have invented a new, original, and ornamental Design for Water Heating Apparatus, of which the following is a specification.

The design is shown in the accompanying drawing, which forms a part thereof, and in which:

Figure 1 is a perspective view of a water heating apparatus showing the new design, while

Figure 2 is a top plan view of the apparatus shown in Figure 1.

I claim:

The ornamental design for a water heating apparatus substantially as shown.

GARRY SANDS.
